FUEL BURNER

Rudolph A. Fenzl, Houston, Tex.

Application October 11, 1935, Serial No. 44,513

3 Claims. (Cl. 158—73)

This invention relates to a fuel burner.

An object of the invention is to provide a burner of the character described specially adapted to utilize either liquid or gaseous fuel, and by the use of which, the fuel may be atomized and mixed with steam, air, or other similar fluid under a pressure higher than the pressure of the furnace where the process of combustion takes place.

Another object is to provide a burner of the character described which may be easily installed and quickly removed and dismantled and which has a wide range of capacities for varying heat requirements by varying the pressures of the fuel and of the steam, air, or other fluid to be mixed therewith.

A still further, and novel feature of the invention resides in the provision of a burner of the character described requiring only low pressures to insure steady operation, thus minimizing vibration during the normal operation of the burner.

A still further object of the invention is to provide a burner of the character described which is of such construction that the fuel will be thoroughly atomized and mixed with the steam, air, or other oxidizing agent before the mixture enters the furnace.

It is a further object of this invention to provide a burner having a novel type of discharge nozzle provided with outwardly flared discharge channels for the delivery of the atomizing agent and bores or ducts leading from the fuel channel and leading into said diverging channels whereby the fuel is caused to be broken up into minute particles and thoroughly mixed with the oxidizing and atomizing agent and forced out of the open ends of the diverging channels in combustible form.

A still further object is to provide a burner of the character described embodying a stationary manifold to which the fuel pipe and the steam pipe may be anchored, and a separate, or detachable manifold clamped to the stationary manifold and forming part of the burner so that the atomizing agent and the fuel can pass from the stationary manifold to the movable manifold without becoming mixed together, and from whence the atomizing agent and the fuel may pass to the atomizing and mixing chambers of the burner.

With the above and other objects in view, the invention has particular relation to certain novel features of construction, operation, and arrangement of parts, an example of which is given in this specification and illustrated in the accompanying drawings wherein:

Fig. 1 shows a longitudinal sectional view of the burner.

Fig. 2 shows a nozzle end view.

Fig. 3 is an inner end view of the deflector.

Fig. 4 shows a cross-sectional view taken on the line 4—4 of Fig. 1, and

Fig. 5 shows a longitudinal sectional view taken on the line 5—5 of Fig. 1.

Referring now more particularly to the drawings wherein like numerals of reference designate similar parts in each of the figures, the numeral 1 designates the stationary manifold and the numeral 2 designates the movable manifold. These manifolds are substantially cylindrical in their external contour. There is an inverted U-shaped yoke 3 which embraces the movable manifold and which is formed with a clamp collar 4 which has a threaded connection with, and surrounds, the stationary manifold 1. A clamp screw 5 is threaded through the cross-bar of the yoke and its inner end bears against the opposing end of the movable manifold 2 shown in Fig. 1, and this screw may be turned by a grip member 6. The abutting parts of the manifolds are provided, one with annular grooves, as 7, and the other with annular ribs, as 8, which fit into said grooves, and annular gaskets 9 are provided between these interfitting parts so as to form tight joints between them. The manifolds may be relatively adjusted, as desired, by loosening the screw 5, or the manifold 2 may be removed for cleansing or replacements. A handle 10 is provided on the manifold 2 for convenience in handling it. The numeral 11 designates the fuel supply pipe which is connected into the end of the stationary manifold 1 and the fuel may pass from the fuel supply pipe through the axial bore 12 of the stationary manifold 1. The movable manifold 2 has also a central bore 13 which is co-axial with the bore 12, but of slightly larger diameter and within the bore 12, there is a cylindrical strainer 14 which is aligned with the bore 12. This strainer extends from end to end of the bore 13 and the fuel is forced to pass through it whereby any clogging particles will be strained out.

In the manifolds 1 and 2, respectively, are the annular chambers 15, 16. The atomizing agent such as steam, air, or the like, may enter the chamber 15 through the inlet pipe 17, and may pass thence through the channels 18 into the chamber 16. There is a tubular outer jacket or shell 19, one end of which is anchored to the movable manifold 2 and communicates with the chamber 16. Arranged concentrically within this shell and spaced from it, there is an inner fuel

pipe 20, one end of which is anchored to the movable manifold and communicates with the bore 13.

Driven, or otherwise secured in the outer end of the shell 19, there is the gland 21 which is outwardly and forwardly flared, as at 22. Secured on the outer end of the fuel pipe 20 is a deflector 23 having the inwardly extended cylindrical shank 24 which is threaded onto the pipe 20. The deflector 23 is also outwardly flared and has the spaced external ribs 24 which diverge outwardly, and whose outer surfaces fit closely against the flared inner face 22 of the gland 21 so as to provide outwardly diverging channels 25. It will be noted from an inspection of Fig. 1 that the face 22 diverges at a greater angle than the external surface 26 of the deflector so that said channels 25 gradually increase outwardly in width as well as in thickness. The inner ends of the channels 25 merge into the bore 27 of the gland 21, through which bore the shank 24 passes. The shank 24 is tubular, and leading from the passageway 28 thereof, there are the radially extending ducts 29 arranged around the deflector, and leading from the bore 28 into the channels 25. In use the atomizing agent such as steam or air, under pressure relatively higher than that of the furnace is supplied through the pipe 17 into the chamber 15 and passes thence to the chamber 16 through the channels 18 and passes thence through the jacket or shield 19 and out through the flared channels 25.

The fuel is supplied under pressure higher than that in the furnace through the supply pipe 11 and passes thence through the bore 12 into the screen 14 and thence out into the bore 13 and through the fuel pipe 20 where it is divided and passes through the small ducts 29 into the outwardly flared channels 25 where the fuel is entrained with the atomizing agent in said channels 25. It is to be here noted that the end of the screen 14 opposite the bore 12 is closed so that all of the fuel must pass through said screen and any foreign objects in the fuel will be screened out. The atomizing agent passes through the bore 27 and through the channels 25 at a high velocity, but since said channels 25 are gradually enlarged toward their discharge ends, the velocity decreases somewhat. The bores 29 for the fuel enter the channels 25 as near the small ends of these last-mentioned channels as practical so that the atomizing agent passing through the channels 25 will sweep by the outer ends of said bores 29 at a high velocity and the atomizing agent will pick up the fuel discharged through the bores 29 and atomize the same into small particles and become thoroughly mixed with it, and the mixture will gradually expand in the

channels 25, thus further breaking up the fuel into finely divided particles which become further mingled with the atomizing agent and the velocity of the mixture will be somewhat reduced and will thus leave the channels 25 at a somewhat lower velocity and in a thoroughly combustible state. 5

The drawings and description disclose what is now considered to be a preferred form of the invention by way of illustration only, while the broad principle of the invention will be defined by the appended claims.

What I claim is:

1. In a fluid burner a nozzle manifold having a bore extending into the manifold, and having an annular chamber around the bore and having a channel extending through the manifold and terminating in said chamber, a jacket connected to the manifold and communicating with the chamber, an inner pipe positioned within the jacket and connected to the manifold and communicating with said bore, a second manifold releasably secured to the nozzle manifold and having passages adapted to align with said bore and channel, and a screen fitted in the bore and adapted to be maintained therein by said second manifold. 20

2. In a fluid burner a nozzle manifold having a bore extending into the manifold, and having an annular chamber around the bore and having channels extending through the manifold and terminating in said chamber, a jacket connected to the manifold and communicating with the chamber, an inner pipe positioned within the jacket and connected to the manifold and communicating with said bore, a second manifold releasably secured to the nozzle manifold and having passages adapted to align with said bore and channels; and a screen fitted in the bore and adapted to be maintained therein by said second manifold, annular ribs on one of said manifolds and the other manifold having grooves to receive said ribs to maintain the manifolds in aligned relationship. 35

3. In a fluid burner a nozzle manifold having a bore extending into the manifold, and having an annular chamber around the bore and having a channel extending through the manifold and terminating in said chamber, a jacket connected to the manifold and communicating with the chamber, an inner pipe connected to the manifold and communicating with said bore, a second manifold releasably secured to the nozzle manifold and a screen fitted in the bore and adapted to be maintained therein by said second manifold. 40
